UNITED STATES PATENT OFFICE.

ALFRED R. BISSETT, OF VANCOUVER, BRITISH COLUMBIA, CANADA.

WRECK-LIFTING DEVICE.

1,129,376.

Specification of Letters Patent. Patented Feb. 23, 1915.

Application filed December 19, 1914. Serial No. 878,049.

To all whom it may concern:

Be it known that I, ALFRED R. BISSETT, a citizen of the Dominion of Canada, residing at Vancouver, in the Province of 5 British Columbia, Canada, have invented certain new and useful Improvements in Wreck-Lifting Devices, of which the following is a specification.

This invention relates to an improvement 10 in the means for lifting submerged wrecks, of that class wherein a series of ropes or chains are passed from one or more floating vessels, around the submerged wreck, which ropes or chains are drawn 15 tight and made fast during low tide, so that as the tide rises and lifts the floating vessel or vessels the submerged wreck is lifted with them in these slings, and may be towed into shoal water, the process being repeated 20 until the vessel is beached or is within a depth that it may be worked on during low water to fit it for removal to a dry dock; or where the rise and fall of the tide is not sufficient, or cannot be depended upon to 25 effect the lifting of the wreck within the required time, the displacement of the floating vessels may be increased and diminished to effect the lifting of the wreck. In dealing 30 in this manner with vessels of any size, the strains imposed on the slinging ropes or chains are considerable and such as necessitate very heavy provision for attachment of them to the floating vessel and in the means by which the ropes are tightened.

35 The invention comprises the arrangement of the tightening windlasses of each rope in such a manner, that the ends of the lifting ropes pass close to one another to their respective tightening windlasses whereby, 40 when the ropes have been tightened, a clamping device may be applied to connect the two ends together. Thus, when the lift takes place the weight of the submerged vessel is suspended in a series of closed 45 slings which pass over the floatable vessel and the tightening windlasses are relieved of all strain due to the lift.

50 The invention is particularly described in the following specification, reference being made to the drawings by which it is accompanied, in which:

Figure 1 shows a cross section of the deck of the floating salvage scow with the tightening windlasses of one wire rope sling. 55 Fig. 2 is a plan of the same. Fig. 3 is a section showing the application of the device

in its simplest form to effect the lifting of a submerged wreck. Fig. 4, an enlarged detail in cross section of the rope tightening wedges, and Figs. 5 and 6, a plan and 60 end elevation showing the application of the device where two or more floating lifting scows are used.

In these drawings 2 represents the hull of a submerged ship and 3 a floating vessel 65 from which a series of slings 4 of chain or wire rope are passed under the submerged wreck 2. One end of each sling 4 is connected to a tightening windlass 5 of any approved design, which windlass is located 70 on the opposite side of the floating vessel to that over which the attached end of the sling cord descends and passes under the wreck, and the other end of the sling cord passes in a similar manner over the other 75 edge of the scow to a tightening windlass 6 located on the opposite side. These two windlasses 5 and 6 located as they are on opposite sides of the middle line of the floatable vessel are in substantially the same 80 plane so that the two ends of the sling as they pass to their respective windlasses are side by side and this enables a clamping device 7 of any suitable character to be applied to secure the ropes or chains together 85 where they pass one another to their respective tightening windlasses. With this arrangement, if the slack of all the slings 4 is taken in by the windlasses and the two ends of each are clamped together during 90 extreme low water, or while the floating vessel 3 has its maximum displacement, as the tide rises, or as the displacement of the floating vessel is reduced, the lifting of the floating vessel 3 will lift the wreck 2 suspended in the several slings. 95

It must be distinctly understood as forming a distinctive feature of this invention that the slings are, by the clamping of the two ends together, practically converted 100 into closed slings passing over the deck of the floating vessel, and the weight of the lift comes entirely on them as such and is distributed over the entire structure of the deck timbers of the floating vessel without 105 attachment to it, and the tightening windlasses 5 and 6 are thus entirely relieved of the tension imposed on the ropes by the lift of the floating vessel whether by the rising tide or by the reduction of the displacement 110 of the vessel. The deck timbers and adjacent structure of the floating vessel are

specially strengthened to stand this load and each sling 4 is retained in alinement with its windlasses by flanged steel shoes 12 secured on each corner where the rope passes over it, which shoes are curved to an ample radius to save the wire rope from undue stress, the ends of the shoe being supported by a chordal web or webs 13.

Without departing from the spirit of this invention, one end of each sling may be anchored to the deck of the floating vessel instead of being connected to one of the tightening windlasses, so long as the ropes pass one another in a manner to enable the clamping device to be applied and save the anchorage from the wreck lifting strain: but the tightening of the slings can be more effectively performed if a windlass is provided for each end of the rope.

In practice, when all the slings 4 have been tightened and clamped, and the weight of the submerged wreck is on them, settlement of the wreck in the slings may leave some of the slings tighter than others, and that each may have its due proportion of the weight of the wreck the slack slings may be tightened by introducing under them a flanged bearing plate 14 with opposed wedges 15. The required tightness of the slings can readily be ascertained by striking them.

As stated, the clamping device may be of any suitable kind that will effect the connection of the two ropes together with a minimum of slip under strain. In the drawing the clamping is shown as effected by a standard wire rope screw clamp applied to grip the two ropes together adjacent each end of one or more edge grooved elliptical pieces inserted between the ropes. This forms a very effective clamp but one will be preferred in which the clamping of each rope can be performed in one movement.

Figs. 5 and 6 show the preferred application of the closed sling principle where one or more of the floating vessels are ranged on each side of the wreck to be lifted. In such case the rope tightening windlasses 5 and 6 may be all on the floating vessel or vessels which are ranged on one side of the wreck, and the several ropes 4 pass from the windlasses 5 across the floating vessel 3 and down and under the wreck, then up and over the floating vessel 8 on the opposite side of the wreck and down and under the wreck again and pass up over the opposite side of the floatable vessel to their windlasses 6 on the opposite side. Thus, when the slings have been tightened by the windlasses and clamped, and the floating vessels 3 and 8 lift with the tide or by their reduced displacement, the wreck to be lifted lies in the double bight of each closed sling. Where the floatable vessels are ranged on each side

of the wreck it will be found advisable to apply struts 10 between them to prevent them closing together under the tendency of the floatable vessels to equalize the tension on the ropes when the ropes might injure the wreck.

By the simple expedient of securing the ends of the lifting ropes together and converting each into a closed sling, in the single or double bight of which sling the submerged wreck may be lifted, the plant and the operation of salvaging under such conditions is simplified and cheapened, as the windlasses by which the ropes of the sling are tightened need only be sufficiently powerful to effect the tightening of the ropes, as when the ends are clamped together the windlasses are entirely free from all strain due to the lift.

No claim is made on the means for lifting a wreck by lines passed under a wreck and connected to a floatable vessel or vessels which lift with the tide or by a reduction of their displacement; but where this system has been used heretofore the ropes have been either made fast to windlasses or to some portion of the structure of the floating vessel, so that the strain is localized in its connection thereto, while in the device hereinbefore described the strain is almost entirely self-contained in the several closed slings, and is by them distributed generally over the deck structure of the floatable vessel, without direct connection of the ropes thereto.

Having now particularly described my invention, I hereby declare that what I claim as new and desire to be protected in by Letters Patent, is:

1. A wreck lifting device, comprising a flexible line passing from a floatable body down and under the wreck to be lifted, means for exerting a tension on the flexible line, and means for securing the two ends of the line together to form a closing sling while that tension is on them.

2. A wreck lifting device, comprising a flexible line passing from each side of a floatable body down to and under the wreck to be lifted the two ends of the line being parallel and close to one another on the floatable body, means for exerting a tension on the line, and means for clamping the two parts of the line together where they are parallel on the floatable vessel.

3. A wreck lifting device, comprising the combination with a floatable vessel, of a series of windlasses arranged in pairs one on each side of the middle line of the vessel in transverse lines, a flexible line connected to each windlass on one side of the middle line and passing across and over the side of the floatable vessel opposite to that on which is the windlass to which it is connected, each line passing under the sub-

merged wreck and up to and over the opposite side of the floatable vessel and connected to the other windlass toward the other side of the middle line, and means for securing 5 together the two parts of each sling where they parallel one another between each pair of windlasses.

4. A wreck lifting device, comprising the combination with a floatable body, of a 10 series of flexible lines passed therefrom down to and under the wreck the two ends of each line passing over opposite sides of the floatable body so that it parallels itself thereon, means for imposing a tension on 15 each line, and means for securing each line together where it parallels itself, and means for varying the tension on individual lines after they have been clamped and the weight of the wreck is on them.

20 5. A wreck lifting device, comprising the combination with a floating vessel, of a flexible line one end of which is connected to the upper side of the floatable vessel between the middle line of the vessel and then 25 passes across the deck of the vessel and down over the opposite side to and under the submerged wreck and up to and over the opposite side of the floatable body to that on which it went down, means for imposing a tension on the sling, and means 30 between the securing means of the two ends of the sling for clamping the lines together.

6. A wreck lifting device, comprising the combination with a floatable vessel having 35 along each side a series of flanged metal shoes each shoe curved to an ample radius

and securely bedded on the deck reinforcing timbers of the vessel the shoes of one side in transverse alinement with those of the other, a windlass on each side of the middle 40 line of the vessel between each pair of shoes, a flexible line connected to one of each pair of windlasses and passing over the shoe on the opposite side of the vessel and down to and under the submerged wreck and up and 45 over the other shoe of each pair to the other windlass of each pair, a clamp securing each flexible line to itself where it parallels itself between the windlasses, a grooved plate between each rope and the deck timbers of the 50 vessel and opposed wedges between the plate and the deck timbers.

7. A wreck lifting device, comprising the combination with a floatable vessel ranged one on each side of a submerged wreck, a 55 flexible line passing across the deck of the vessel on one side of the wreck and under the submerged wreck, each end of the line connected to a windlass on the opposite side of the other floatable vessel to that over 60 which it passes, means for clamping the two portions of each line together between the windlasses, and double wedges applied under each line on the floatable vessel which the loop of the line passes over.

65 In testimony whereof I affix my signature in presence of two witnesses.

ALFRED R. BISSETT.
